UNITED STATES PATENT OFFICE.

ARTHUR W. BANISTER, OF DORCHESTER, MASSACHUSETTS; EMMA J. BANISTER, OF BOSTON, MASSACHUSETTS, ADMINISTRATRIX OF SAID ARTHUR W. BANISTER, DECEASED.

VENTILATOR.

1,174,038.

Specification of Letters Patent.

Patented Mar. 7, 1916.

Application filed April 29, 1913. Serial No. 764,364.

To all whom it may concern:

Be it known that I, ARTHUR W. BANISTER, a citizen of the United States, and resident of Dorchester, in the county of Suffolk and 5 Commonwealth of Massachusetts, have invented an Improvement in Ventilators, of which the following description, in connection with the accompanying drawings, is a specification, like characters on the drawings representing like parts.

This invention relates to ventilators for chimneys or flues, and among other objects provides a simple and effective construction.

The character of the invention may be 15 best understood by reference to the following description of an illustrative embodiment thereof shown in the accompanying drawing, wherein:

Figure 1 is a vertical section through an 20 illustrative ventilator shown herein as embodying the invention; and Fig. 2 is a section taken on line 2—2 of Fig. 1.

Referring to the drawing, the illustrative 25 ventilator shown therein as embodying the invention comprises a chimney or flue 1 on which is mounted a duct or funnel 3 flared toward its delivery end to facilitate the discharge of air or other gas from the flue 1, as more fully hereinafter described. De- 30 pending from said funnel is a collar 5 preferably spaced somewhat from the tube 1 to permit an upward draft of air therethrough.

Within the funnel 3 is a duct 7 having a 35 flared end fitted into and secured to the windward end of the outer duct 3. This inner duct extends a substantial distance within the outer duct and across the upward flue a substantial distance above the latter. It will be observed that the outer and inner 40 ducts diverge in opposite directions. The convergence of the inner duct tends to accelerate the passage of air therethrough and thereby promotes a draft or suction up through the flue 1. The inner duct is 45 formed to present an inclined portion 9 which deflects the gases from the flue 1 toward the discharge end of the funnel 3.

An important feature of the invention relates to the pivotal mounting of the ducts 50 on the flue 1. To this end there is provided a spindle or shaft 11 supported by brackets 13 and 15 extending across the flue 1 adjacent the upper and lower ends thereof. This spindle projects above the flue toward 55 the under face of the inner duct 7 and

passes through a bearing bracket 17 extending across and secured to the neck 5 of the funnel 3. The upper end of this spindle is tapered to receive an end thrust bearing block 19 secured to the under face of the 60 duct 7. It will be observed that the spindle does not project into the inner duct 7, but on the contrary terminates beneath the under side thereof, thereby leaving the duct unobstructed and permitting the free pas- 65 sage of air therethrough. Also the spindle projects but a slight distance above the neck 5 and offers but a minimum obstruction to the funnel 3. This pivotal connection between the inner duct and the flue 1 is an 70 extremely simple construction, facilitating the ready assembly of the parts and permits the rotation of the ducts about the flue 1 with very slight frictional resistance.

To turn the ducts on the spindle, as de- 75 scribed, so as to present the entrance end of the inner duct 7 toward the wind the funnel 3 may be provided on its upper side with an appropriate vane 23.

It frequently happens that these chimney 80 ventilators must be located near a wall, such for example as that of an adjacent building. The impact of air against such wall would tend to slow up the air current, but by the funnel shaped tube 7 the velocity of the air 85 is increased so that under such circumstances it is effective in promoting the draft. The funnel 3 in flaring in an opposite direction from the inner tube 7, compensates for the obstruction thereof by the inner duct and 90 provides for the free egress of the currents in their passages from the fixed flue 1.

It will be observed that the windward end of the ventilator tube 7 is closed to the fixed flue 1. By virtue of the vane 23 the venti- 95 lator is always turned to present said end to the wind. As a result, there can be no possibility of downward puffs in the fixed flue 1, but on the contrary a continuous upward draft through said flue is maintained.

Having described one embodiment of the invention, without limiting the same there- 100 to, what I claim as new and desire to secure by Letters Patent is:

A ventilator comprising in combination, 105 an upright flue, oppositely diverging outer and inner ducts, the outer duct having a discharge end substantially larger than the inlet end of the inner duct, the smaller end of said outer duct being secured rigidly di- 110

rectly to the larger end of said inner duct, said inner duct having a contracted passage portion offset upward from the central axial line of its larger end and a wall sharply inclined from said larger end upward to said portion, for leaving a large free passage above said flue for conducting gases from the latter to the discharge mouth of said outer duct, a vane for directing said ducts,

and means providing a pivotal mounting 10 for said ducts on said flue.

In testimony whereof, I have signed my name to this specification, in the presence of two subscribing witnesses.

ARTHUR W. BANISTER.
